US0D1067223S

(12) **United States Design Patent** (10) **Patent No.:** **US D1,067,223 S**
(45) **Date of Patent:** **** Mar. 18, 2025**

(54) **SOUND GENERATOR**

- (71) Applicant: **Bencoo, Inc.**, Chino, CA (US)
(72) Inventor: **Jennifer Glaser**, Pasadena, CA (US)
(**) Term: **15 Years**
(21) Appl. No.: **29/821,944**
(22) Filed: **Jan. 4, 2022**
(51) LOC (15) Cl. **30-99**
(52) U.S. Cl.
USPC **D30/199; D10/119.3**
(58) **Field of Classification Search**
USPC D30/160, 199; D14/299; D21/405;
D10/119.1, 119.2, 119.3
CPC A01K 15/026
See application file for complete search history.

(57) **CLAIM**

The ornamental design for a sound generator as shown and described.

DESCRIPTION

FIG. 1 is a front perspective view of a sound generator showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view thereof taken along the line 8-8 of FIG. 2;

FIG. 9 is an exploded view thereof;

FIG. 10 is another exploded view thereof;

FIG. 11 is a second perspective view of the sound generator; and,

FIG. 12 is a third perspective view of the sound generator. The broken lines in FIGS. 1-10 are for the purpose of illustrating portions of the sound generator that form no part of the claimed design.

1 Claim, 12 Drawing Sheets
